(57) **CLAIM**

The ornamental design for a rear fascia lower applique, as shown and described.

DESCRIPTION

FIG. 1 is a front perspective view of a rear fascia lower applique showing our new design;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

It will be understood that the broken lines shown in the drawings illustrate portions of the rear fascia lower applique that form no part of the claimed design.

1 Claim, 5 Drawing Sheets
